UNITED STATES PATENT OFFICE.

CHARLES LAWRENCE STOKES, OF LOS ANGELES, CALIFORNIA, ASSIGNOR TO CURTIS B. CAMP, TRUSTEE, OF GLENCOE, ILLINOIS.

AUTOMATIC FUEL REGULATOR.

Application filed September 15, 1925. Serial No. 56,513.

My invention relates to improvements in apparatus for automatically regulating and controlling the priming mixture for starting an internal combustion engine.

5 The principal object of my invention is to provide a simplified apparatus wherein a rich priming charge is delivered to an internal combustion engine by its suction at low temperatures, the volume of the rich 10 charge being suddenly reduced as soon as the engine has started and thereafter the volume of the charge being further gradually reduced as the engine warms up and finally positively cutting off the priming 15 charge when the engine has reached an optimum operating temperature.

Another object of my invention is to provide simplified and improved means for the application of my method allowed in my co-pending application Serial No. 644,923 filed June 12, 1923.

Referring to the drawings in which the same numbers indicate like parts:

Fig. 1 is a vertical view, partly in section, 25 showing the application of my improved apparatus.

Fig. 2 is a section along the lines A—A of Fig. 1.

30 A carburetor 1 of any well known make is provided with an intake pipe 2 with which it is connected with an internal combustion engine for supplying the same in any well known manner with a combustible mixture of air and liquid fuel, the air being supplied through a passage 3 and the fuel being supplied from a float chamber 4 and the supply of combustible mixture for operating the engine normally is controlled by a butterfly valve 5.

40 In starting an internal combustion engine at low temperatures, however, it is always necessary to rely on an over-supply of liquid fuel to start the engine and keep it running until such time as the engine may attain an operating temperature without excess fuel.

45 In the present instance this is done by attaching a casing 6 in any well known manner to the intake pipe 2 on the engine side of throttle 5. Casing 6 contains a reciprocating valve 7 adapted to slide therein and valve 7 terminates in a small valve point 8 containing a plurality of orifices 9 and point 8 is adapted to be seated primarily by the engine suction in an orifice 11 giving admission of fuel and air for priming purposes

to the interior of intake pipe 2. When valve 7 is normally at rest, as for instance when the engine is stopped, point 8 will be withheld from orifice 11 by means of a spring 10.

50 The casing 6 is arranged to receive a fuel, or fuel and air, nipple 12 adapted to be controlled by valve 13 and a pipe 14 conveys liquid fuel to nipple 12 from the float chamber 4. An air valve 15 is provided for admitting air, if desired, to the pipe 14 when liquid fuel is being drawn therethrough by the engine suction. An air nipple 15 is also fitted to casing 6 for passing air therein and the passage of said air is controlled by valve 17.

55 Centrally of casing 6 is a valve 18 having thereon a head 19 adapted to close the interior of 8 and thereby the orifices 9, the other end of 18 being threaded to receive 75 guide nuts 26 and 27 adjustably held in position respectively by lock nuts 28 and 29 and holding therebetween one end of a bimetallic thermostat 25. A portion of 18 is squared at 20 to be guided in a spider 21 containing a plurality of orifices 22. A 80 valve 23 governs the admission of liquid fuel to the pipe 14 from the float chamber 4 and liquid fuel is conveyed also by a pipe 24 to the engine side of valve 7 when the same is normally at rest for cranking vacuums.

85 When the engine has fired and idling vacuum is applied to valve 7, pipe 24 will be covered by valve 7. Thermostat 25 is fastened to a portion of the engine 30 where it is subjected to variations of the engine temperature. Such may be accomplished in many ways by exposing thermostat 25 to the influence of the circulating water, the exhaust gases, or to the intake air supplied to carburetor 1 and preferably I use this latter 90 method wherein a hot air stove 31 surrounds the exhaust pipe 33 and also the thermostat 25, the heated air being drawn into passage 3 through a flexible tubing (not shown) connecting passage 3 and passage 34 leading 100 from the interior of stove 31 to the end that heated air will be continuously applied to the thermostat 25.

105 The operation of this device is as follows:

Preferably on starting an internal combustion engine, the butterfly valve 5 is closed whereupon the engine being cranked by the usual self starter, a predetermined degree of vacuum will prevail on the engine side of throttle 5. If it be assumed that this 110

vacuum at cranking speeds is nine inches of mercury in the intake passage 2, same will be applied through 11 to move the valve 7 a predetermined distance away from head 19 and also to draw a stream of liquid fuel through pipe 24 to start the engine. This movement also permits the application of said vacuum through the orifices 9 and 22 to the air passage 16 and the fuel passage 10. 12. If it now be assumed that valve 15 is closed and valves 13 and 17 properly regulated it will be seen that liquid fuel will be drawn from 4 through the parts mentioned to the interior of 2, the passage of the liquid fuel being hastened by the admission of the proper proportion of air to the pipe 16 and this mixture of liquid fuel and air is designed to be sufficient to start the engine quickly. 20. As soon as the engine fires, the idling speed being greater than the cranking speed, the vacuum in intake 2 will jump to about eighteen inches of mercury vacuum which vacuum thereupon tends to draw the point 25 8 to close the orifice 11 thus reducing immediately after starting the amount of liquid fuel and air supplied in excess of the normal carburetor fuel controls (which latter are not shown in this drawing) by initially 30 closing off pipe 24. It will be seen that the area of orifice 11 is relatively small as compared with the area of valve 7 and therefore valve 7 will not be retained by the high vacuum to effectively close orifice 11 under 35 normal conditions except where the area of orifice 11 is over one-half times as large as the area of valve 7 therefore there will be a minute movement of valve 7 permitting a slight opening past the point 8 to the end that a diminished vacuum will be applied 40 for drawing a diminished quantity of fuel and air through passages 12 and 16 to the intake 2.

If this diminished quantity of fuel and air is insufficient to keep the engine running 45 and the speed of the same will diminish, the vacuum in 2 will thereby diminish whereupon point 8 will be further forced from the orifice 11 by the spring 10 to the end that the vacuum is immediately increased for drawing augmented supplies of liquid fuel and air and thus automatically priming the engine again.

After the engine is fired, and within a predetermined time, the heat from exhaust pipe 33 will be effective for reflection on the thermostat 25 whereby valve 18 will be moved to increasingly, and finally, force valve 7 to its seat in orifice 11 and at the same time head 19 will completely cut off the supply of liquid fuel and air for priming purposes to the intake 2. Inasmuch as pipe 24 has already been covered by the initial movement of valve 7 due to the engine vacuum when idling, it will thus be seen 65 that the supply of priming fuel will be ab-

solutely cut off from the engine when the same is running at operating temperatures. At the same time it must be noted that the thermostat 25 provides a time element varying with atmospheric temperatures and thus 70 I am enabled to automatically take care of all conditions for priming a particular engine.

It may be noted that valve 15, 13, 17 and 23 may be eliminated for any particular 75 engine and set orifices provided in their place but generally, at least for experimental purposes, it is advisable to provide the adjustments mentioned inasmuch as it hastens the standardization for any particular type of 80 engine and at the same time gives an opportunity for varying the controls to obtain optimum operation.

I claim:

1. In a priming device, an intake manifold 85 for an internal combustion engine, a carburetor attached thereto, a fuel reservoir supplying the carburetor with liquid fuel, means for initially supplying a rich priming charge of fuel and air to the intake 90 manifold at a point above the throttle from the reservoir responsive to the engine suction and means responsive to the engine suction and temperature for cutting off said priming charge from the intake manifold. 95

2. In a primary device, an intake manifold for an internal combustion engine, a carburetor attached thereto, a fuel reservoir supplying the carburetor with liquid fuel, a casing connected with the manifold, a valve actuated by the engine suction in the casing for regulating the connection between the intake manifold and the casing, means to supply liquid fuel from the reservoir to the casing and means responsive to the engine suction and temperature for controlling the position of said valve. 105

3. In a priming device, an intake pipe for an internal combustion engine, a throttle in said pipe, a carburetor associated therewith, a fuel reservoir for supplying fuel to said carburetor, means for automatically supplying a stream of liquid fuel to said intake pipe at a point above said throttle at cranking speed, and means for automatically 110 supplying a mixture of air and fuel through said first named means to said intake pipe above said throttle at engine speed with closed throttle during the initial operation of the engine. 115

4. In a fuel feeding system for internal combustion engines, an intake passage, a throttle in said passage, a carburetor for supplying fuel to said passage, a pair of passages for conducting fuel from said carburetor to said intake passage above said throttle, and means operated by the suction of the engine for closing one of said passages, and thermally controlled means for automatically closing the other passage when 125 120 125 130

the engine reaches a predetermined temperature.

5. In a fuel feeding system for internal combustion engines, an intake passage, a throttle in said passage, means including a fuel reservoir for supplying fuel to said passage, a plurality of auxiliary passages for supplying fuel to said intake passage at a point above said throttle, means operated by the suction of the engine for closing certain of said passages, and thermally controlled means for closing the other of said passages.

6. In a fuel feeding system for internal combustion engines, an intake passage, a throttle in the passage, means including a fuel reservoir for supplying fuel to said passage, a port in said passage above said throttle, an auxiliary passage for supplying fuel to said intake passage through said port, means for supplying air to said auxiliary passage and port, suction-controlled means for intercepting the flow of fuel through said auxiliary port and means for automatically controlling the flow of air through said auxiliary passage.

7. In a fuel feeding system for internal combustion engines, an intake pipe having a port therein, a throttle below said port, means for supplying liquid fuel through said port on starting said engine with closed throttle, means for supplying air and fuel through said port after the starting of the engine and before the same reaches its normal running temperature, and means for

closing said port when said engine reaches a predetermined temperature.

8. In a fuel feeding system for internal combustion engines, an intake pipe having a port therein, a throttle in said pipe below said port, means for supplying an explosive mixture to said pipe below said throttle, and means for first supplying liquid fuel and then a mixture of fuel and air to said intake pipe above said throttle while said engine is warming up and for closing said port when said engine reaches a predetermined temperature.

9. In a fuel feeding system for internal combustion engines, an intake pipe having a port therein, a throttle below said port, a chamber surrounding said port, passages for supplying fuel to said chamber, a tubular suction valve for closing one of said passages slidably mounted in said chamber and provided with a reduced portion, said reduced portion forming a valve seat and having its end tapered to engage said port, said tapered end being provided with an opening, a spring for resisting the inward movement of said valve, a thermally controlled valve for engaging said seat and for forcing said suction valve to close said port, and thermally controlled means for operating said thermally controlled valve.

Signed at Wilmington, in the county of Los Angeles, and State of California, this 21st day of March, A. D. 1924.

CHARLES LAWRENCE STOKES.
